WILLIAM GRIESBACH, OF GREENFIELD, MASSACHUSETTS.

HOLDER FOR PRICE TAGS.

Application filed February 12, 1924. Serial No. 692,361.

To all whom it may concern:

Be it known that I, WILLIAM GRIESBACH, a citizen of the United States, residing at Greenfield, in the county of Franklin and State of Massachusetts, have invented new and useful Improvements in Holders for Price Tags, of which the following is a specification.

This invention relates to improvements in holders for price tags for suitably marking or indicating the price of commodities of various kinds in stores, particularly in stores containing groceries. An object of the invention is to provide a device for permitting the insertion and removal of the price ticket or tag, without disturbing the contents of a package or those on a shelf. It is designed to be attached to the shelf on which the goods are displayed or placed in a carton or receptacle.

Broadly, it comprises a member consisting of a strip of metal which is formed on its opposite edges with bent over portions to provide channel ways so that the tag or ticket may be readily moved longitudinally after being inserted, or if desired it may be reversed to indicate a different price on its reverse side.

Referring to the drawings:

Fig. 1 is a perspective view of the holder showing a portion of a shelf on which the goods are displayed or located, and illustrating the device attached to the edge of the shelf.

Fig. 2 is a detail view, partly in section, showing the holder removed from the shelf and illustrating the opening in the upper edge of the device for the insertion of the price tag or ticket.

Fig. 3 is a perspective view of a modification of the holder, and

Fig. 4 is a top plan view of Fig. 3.

Referring to the drawings in detail:

1 designates a strip of metal having the bent or folded over upper and lower portions 2 and 3 for forming the channel ways 4 and 5. 6 designates an opening or slot

which is formed in the bent over portion 2 for providing an opening for inserting the price tag or ticket 7. Fig. 2 shows in dotted lines the tag before it is passed or dropped through the opening 6 into the position shown. After it is inserted it may be moved longitudinally of the holder 1 or it may be left in a position immediately below the opening 6 in order to properly designate the price of the article immediately located above the price tag.

Referring to Figs. 3 and 4 which shows a modification, the opening 6 is provided with a tag guiding portion or part 8, which portion is formed by bending the removed portion of the part 2 rearwardly so that the ticket or price tag 7 engages the surface 8' and serves as a guide to assist the user in inserting the price ticket.

It will be seen from this description that I have perfected a very efficient and inexpensive holder device for price tags or cards indicating the price of articles, and one that permits the ready insertion and removal of the price tag or card. Heretofore, it has been a common expedient to tack or nail the card to the shelf with the result that the shelf is disfigured which produces an unsightly appearance.

What I claim is:

1. A holder for price tags comprising a member having bent over edges to provide channel portions to receive a tag, one of the bent over edges having openings therethrough to insert and remove a tag and the opening being provided with a guiding surface which is an integral part of the bent over edge.

2. A price tag holder comprising a one piece member formed with channel portions to retain a tag in place, said member having a bent over upper edge with an opening for inserting a tag, the edge of the opening having a part to guide the tag when it is being inserted as described.

WILLIAM GRIESBACH.
